UNITED STATES PATENT OFFICE.

AGNES P. HANDLEY, OF OAKLAND, CALIFORNIA, ASSIGNOR TO LEROY ALLIGER, OF
PALO ALTO, CALIFORNIA.

DESIGN FOR A TOY RABBIT.

Application filed April 25, 1922. Serial No. 1,964. Term of patent 7 years.

To all whom it may concern:

Be it known that I, AGNES P. HANDLEY, a citizen of the United States, residing at Oakland, in the county of Alameda and State of California, have invented a new, original, and ornamental Design for a Toy Rabbit, of which the following is a specification, reference being had to the accompanying drawing, forming part thereof.

The figure is a perspective view of a toy rabbit showing my new design.

I claim:

The ornamental design for a toy rabbit, as shown.

In testimony whereof I affix my signature.

AGNES P. HANDLEY.
